UNITED STATES PATENT OFFICE.

JOSHUA KING NORTHRUP, OF ELLICOTTVILLE, NEW YORK.

SHOE LAST.

Application filed November 2, 1922. Serial No. 598,513.

To all whom it may concern:

Be it known that I, JOSHUA KING NORTHRUP, a citizen of the United States, residing at Ellicottville, in the county of 5 Cattaraugus and State of New York, have invented new and useful Improvements in Shoe Lasts, of which the following is a specification.

This invention relates generally to lasts, 10 but more particularly to a sectional last whose heel part is detachable from its fore part.

One of the principal expenses in the manufacture of shoes is the cost of the lasts, one 15 last serving for a comparatively few pairs of shoes, after which it is discarded for a new one. Still further expense is incurred in that it is necessary to make new lasts to accord with the styles as they change from 20 season to season. At the present time, these lasts are made of one of our most valuable timbers of which the country is fast being stripped.

One of the chief objects of this invention 25 is the construction of an inexpensive last which is considerably more durable than those hitherto in use, thereby effecting a marked saving in the cost of shoe manufacture.

30 A further object is to provide improved means for detachably locking the parts of the last together.

In the accompanying drawings:

Figure 1 is a longitudinal section of the 35 improved last taken in the plane of line 1—1, Fig. 2. Figure 2 is a bottom plan view thereof. Figure 3 is a transverse section on line 3—3, Fig. 1. Figure 4 is an enlarged sectional view of the means for detachably holding the parts of the last together. Figure 5 is a horizontal section on line 5—5, Fig. 4.

Similar characters of reference indicate corresponding parts throughout the several views.

45 The invention is illustrated in connection with a two-part last consisting of a heel part 10 and a fore part 11 which are slidably and detachably connected along the substantially vertical joint-line 12. The ad- 50 joining faces of these parts are provided with oppositely-facing shoulders 13, 14 to insure the top and bottom portions of the heel section being flush with the corresponding portions of the fore part section when said parts are assembled. To hold 55 the sections against pulling apart length-

wise, one of them is provided with a dovetail tongue 15 which engages a corresponding groove 16 in the other part.

It will be noted, as shown in Figs. 1 and 60 4, that the joint-line 12 inclines or slants forwardly from the bottom to the top of the last. This construction permits the necessary shortening action of the last to enable the heel part to be removed from the shoe 65 without affecting the fore part.

The last sections are preferably constructed of metal and I propose to make the heel part 10 of cast steel and the fore part 11 of aluminum or like light metal or of 70 hollow cast steel. The bottom of said fore part is preferably provided with a recess or socket 17 for receiving a renewable sole portion 18 of wood or similar material. The latter may be securely fastened to the last- 75 section by a screw 19 or other means. When this wooden sole portion becomes worn out from use, it is only necessary to substitute a new one for it, while the last-body itself can be used repeatedly, thus affording a sav- 80 ing of material and reducing the cost of the manufacture of shoes accordingly. By making the fore part of the last of aluminum, the same can be melted and recast into different shapes, to suit the changing 85 styles of shoes, thus rendering it unnecessary to throw the last away. Practically no change in style is ever made in the heel of the shoe, so that that section can be used continuously with differently-shaped fore- 90 part sections.

To hold the parts of the last securely together and prevent any relative sliding movement thereof, a locking device is provided which is preferably constructed as 95 follows:

The heel section 10 is provided with the usual jack-spindle socket 20 and arranged at substantially right angles thereto, and opening into the lower end of said socket 100 is a hole 21 which extends to the front face of said section. Arranged in this hole is a sleeve 22 and a bushing 23, the latter being located in front of the former and flush with the face of the heel section. The fore-part 105 11 is provided with a socket 24 in axial alignment with the hole 21 and of the same diameter as the bore of the bushing 23. A spring-pressed locking bolt 25 is slidably mounted in the socket 24 and is adapted to project 110 into the bushing 23, its spring 26 normally holding said bolt in its locked or projected

position for preventing relative vertical displacement of the last sections, as shown in Fig. 1. Co-operating with this locking bolt and slidably mounted within the sleeve 22 and the bushing 23 is a releasing pin or bolt 27 to which is applied a spring 28 normally tending to hold it in its retracted position.

A key 29 is employed for projecting the releasing bolt and retracting the locking bolt 10 sufficiently to permit the separation of the last sections. As shown in Fig. 5, the web 30 of this key is cam-shaped and when inserted in the jack-spindle socket 20, occupies the enlarged space 31 formed in the lower 15 end of said socket in line with the hole 21, as shown in Fig. 4. The maximum diameter of the key-web including its shank is slightly less than the diameter of the spindle socket, so that the key can be freely passed 20 through the latter into its operative position. In the unlocked position of the parts shown in Fig. 4, the key-web extends forwardly beyond the socket 20 and beneath the shoulder 32 formed by the enlargement 31, 25 so that it becomes interlocked with the heel section when the withdrawal of the key is attempted. By this arrangement, the key also constitutes a handle for conveniently lifting and detaching the heel section of the 30 last from its companion section.

I claim as my invention:

1. A shoe last comprising separable, slidably connected heel and fore part sections having an interlocking tongue and a groove, the heel section having a socket, a spring-pressed locking bolt mounted in one of said sections and normally projecting into the other section, and a spring-pressed releasing bolt mounted in said last-named section and arranged to engage said locking bolt, said 40 releasing bolt normally projecting into the heel-socket for engagement with an unlocking device employed for operating said releasing bolt and withdrawing the last section from the shoe. 45

2. A shoe last comprising separable, slidably connected heel and fore part sections, the heel section having a spindle-socket terminating at its bottom in an offset enlargement, a spring-pressed locking bolt mounted 50 in one of said sections and normally projecting into the other section, and a spring-pressed releasing bolt mounted in said last-named section and normally extending into the offset enlargement of said spindle socket 55 for engagement with an unlocking device insertable into the socket for actuating said locking bolt and withdrawing the last section from the shoe.

JOSHUA KING NORTHRUP.
